UNITED STATES PATENT OFFICE.

HUGH LYONS, OF LANSING, MICHIGAN.

HAND FOR DISPLAY-FORMS.

SPECIFICATION forming part of Letters Patent No. 620,598, dated March 7, 1899.

Application filed July 29, 1897. Serial No. 646,349. (No model.)

To all whom it may concern:

Be it known that I, HUGH LYONS, a citizen of the United States, residing at the city of Lansing, in the county of Ingham and State 5 of Michigan, have invented a certain new and useful Improvement in Hands for Display-Forms, of which the following is a specification.

My invention relates to improvements in 10 artificial hands for display-forms, dolls, and for similar purposes.

The objects of this invention are, first, to provide an artificial hand which is cheap to produce and is very flexible and that can be 15 placed in any position required or desired, and, second, to produce a construction of artificial hand in which it is possible to utilize comparatively cheap material and yet secure the desirable results of flexibility and shape- 20 liness.

Further objects will definitely appear in the detailed description to follow.

I accomplish these objects of my invention by devices and means described in the following specification, pointed out in the claims, 25 and illustrated in the accompanying drawings, in which—

Figure 1 is a perspective view of the skeleton portion of the hand. Fig. 2 is a perspective view of the hand in process of construction. Fig. 3 is a perspective view of the hand 30 when completed.

In the drawings similar letters of reference refer to similar parts throughout the several 35 views.

Referring to lettered parts of the drawings, A represents the block forming the body of the hand, and on or within which is provided a suitable means of attaching the same to an 40 arm. Inserted into the block are pieces of copper wire B, corresponding to the fingers of the hand in position to form the centers thereof. A piece of wire B' is inserted into one side of the block A to serve for the thumb. 45 The wire preferably employed is copper wire, though any properly annealed metal or any similar material might be employed for the purpose instead.

When the skeleton of the hand is formed

as indicated in Fig. 1, suitable padding, consisting of wadding or pieces of cloth or the like, is distributed over the block to shape the same like the hand. This is secured in place by a suitable covering of cloth, preferably torn in strips and wound thereon. The 50 digits of the hand are filled out by strips of cloth in layers wrapped spirally around the same. By this means the cloth forming the padding or filling of the digits will move upon itself, so that the digits can be bended without disarranging the padding or causing a change in their shape, thus making the hand 55 very durable.

When the hand is filled out to the proper form, a glove-like covering D is placed over 60 the same. I desire to state in this connection that while I have specified strips of cloth wound spirally, yet I am aware that strips of soft leather or any similar material might be employed for the purpose of covering the 65 wires forming the digits.

Having thus described my invention, what I claim as new, and desire to secure by Letters Patent, is—

1. In an artificial hand for display-forms or 70 similar purposes, the combination of the central body-block A; flexible copper wire B secured thereto to form the core of the fingers, and a flexible copper wire B' secured to one side and projecting out to form the thumb; 75 suitable padding placed over the central body-block; and strips of fabric or similar flexible material wound thereon and wound spirally on the wires B' to make up the digits; and a glove-like covering D fitted over the whole 80 for the purpose specified.

2. In an artificial hand for display-forms and similar purposes, the combination of the central body-block; flexible wires secured thereto and extending out to form the cores 90 of the fingers and a flexible wire secured to one side and projecting out to form the core of the thumb; strips of fabric or similar flexible material wound spirally on the said wires to make up the digits; and a glove-like covering fitted over the whole for the purpose 95 specified.

3. In an artificial hand for display-forms

and similar purposes the combination of the central body-block; flexible wires secured thereto and extending out to form the cores of the fingers; strips of fabric or similar flexible material wound spirally on the said wires to make up the digits for the purpose specified.

In witness whereof I have hereunto set my hand and seal in the presence of two witnesses.

HUGH LYONS. [L. S.]
